CLAIM

The ornamental design for a quick change accelerator tube assembly for hydraulic food cutter, as shown.

DESCRIPTION

FIG. 1 is a perspective view of a quick change accelerator tube assembly for hydraulic food cutter showing my new design;

FIG. 2 is a side elevational view thereof;

FIG. 3 is a top plan view thereof; and,

FIG. 4 is a bottom plan view thereof.

1 Claim, 1 Drawing Sheet

FIG. 4
